Primary Examiner — Eric L Goodman*Assistant Examiner* — Michelle D McCord(74) *Attorney, Agent, or Firm* — Bradley J. Shelowitz(57) **CLAIM**

The ornamental design for a backrest of a rollator, as shown and described.

DESCRIPTION

FIG. 1 is a front perspective view of a backrest of a rollator; and,

FIG. 2 is a rear perspective view thereof.

The broken lines showing parts of the backrest of a rollator are for the purpose of illustrating portions of the backrest of a rollator that form no part of the claimed design.
